UNITED STATES PATENT OFFICE.

DELOS C. WHITFORD, OF WOLCOTT, NEW YORK.

DESIGN FOR A HAMMER-HEAD.

SPECIFICATION forming part of Design No. 32,402, dated March 27, 1900.

Application filed February 17, 1900. Serial No. 5,652. Term of patent 14 years.

To all whom it may concern:

Be it known that I, DELOS C. WHITFORD, a citizen of the United States, residing at Wolcott, in the county of Wayne and State of New York, have invented and produced a new and original Design for a Hammer-Head, of which the following is a specification.

This invention relates to a new and original design for a hammer-head, and the essential 10 feature resides in the particular semicircular plinth shape of an extension on the outer edge.

In the accompanying drawing the figure represents a perspective view of a hammer-head embodying the features of the design, 15 and referring thereto the numeral 1 designates a cylindrical arm projecting from one side of an intermediate body 2, having corresponding flat faces 3 on opposite sides. 20 From the opposite side of the body 2 projects a downwardly-directed converged claw 4, having its upper and lower edges curved and its opposite faces flat.

Depending from the body 2 intermediate of the cylindrical projection 1 and the claw 25 4 is a trapezoid-shaped socket 5, and directly above the same and extending from the outer edge of the said body is a semicircular plinth-shaped extension 6, having a rectangular opening 7 therein. The outer curved edge 30 of the claw 4 gradually merges into the adjacent curved edge of the extension 6, and at the opposite side the said extension abruptly meets the inner portion of the projection 1.

Having thus described the invention, what 35 is claimed as new is—

The design for a hammer-head, herein shown and described.

In testimony that I claim the foregoing as my own I have hereto affixed my signature in 40 the presence of two witnesses.

DELOS C. WHITFORD.
